UNITED STATES PATENT OFFICE.

JOSEPH B. BARIANI, OF ENCAMPMENT, WYOMING.

AUTOMATIC OILING DEVICE.

No. 895,532.

Specification of Letters Patent. Patented Aug. 11, 1908.

Application filed May 23, 1907. Serial No. 376,140.

To all whom it may concern:

Be it known that I, JOSEPH B. BARIANI, a citizen of the United States, residing at Encampment, in the county of Carbon and State 5 of Wyoming, have invented certain new and useful Improvements in Automatic Oiling Devices, of which the following is a specification, reference being had therein to the accompanying drawing.

10 My invention is an automatic pump oiler for use upon the carriage of a tramway bucket or the like in oiling the track cable.

15 The object of the invention is to provide a device of this character which will be simple and practical in construction and entirely automatic in its operation.

20 With the above and other objects in view the invention consists in the novel construction and the combination of parts hereinafter described and claimed, and illustrated in the accompanying drawings, in which

25 Figure 1 is a side elevation of a tramway bucket, its carriage and track cable, showing the application of my invention thereto; Fig. 2 is a detail vertical section taken on the plane indicated by the line 2—2 in Fig. 1; and Fig. 3 is a detail section through the pump.

30 In the drawings, 1 denotes a tramway bucket or the like suspended from a carriage 2 which is provided with grooved supporting wheels 3, 4 to run upon a track rope or cable 5.

35 The numeral 6 denotes my improved automatic pump oiler for oiling the cable 5. It comprises an oil reservoir or container 7 suitably supported from the carriage 2 and having a suction feed pipe 8 leading from it to a pump 9. The latter may be of any suitable form and construction but as shown it has a vertical cylinder secured in a base 9^a arranged 40 upon the horizontal upper portion of an upright bracket or support 10 on the carriage 2. The base 9^a is formed upon its bottom with a tubular inlet projection 9^b, to the lower end of which is connected the pipe 8^a and at the 45 upper end of which is a hinged valve 9^c. Upon one side of the base 9^a is formed an extension provided with a discharge passage or opening and a hinged valve 9^d. 15 denotes a discharge pipe having one end connected to 50 said projection or extension and in communication with its discharge passage and its other end connected to the lower end of a vertical chamber or cylinder 16 also mounted upon the bracket 10. Projecting horizontally 55 from the chamber 16 adjacent to its top is a discharge or outlet pipe 17 having two ver-

tically extending branches 18, 19 leading from its outer end. By providing the chamber 16 and arranging the outlet pipe 17 adjacent to its top and the connecting pipe 15 with the valve 9^d adjacent to its lower end, it will be seen that said chamber and the pipe 15 will be constantly filled with oil up to the level of the pipe 17 so that as soon as the pump is started the oil will be forced from the chamber 16 and out of the pipe 17. The space in the upper portion of the chamber 16 above the pipe 17 also serves the purpose of an air cushion. The pump is provided with a reciprocating piston having a rod 11 connected to the upper end of a pitman 12, which latter has its lower end connected to a crank 13 fixed on the shaft or journal 14 of the grooved wheel 3. The branch 18 extends downwardly to the carriage 2 and is provided 75 with a suitable regulating valve 20 and a discharge nozzle 21. The latter is rearwardly turned and so arranged as to drop or discharge oil upon the cable or track 5 between the two wheels 3, 4. The upper branch 19 80 serves as an overflow pipe and extends rearwardly and then downwardly, as at 22, so as to discharge into the oil reservoir 7.

85 The operation of the invention is as follows: When the carriage 2 moves in the direction of the arrow in Fig. 1, the movement of the wheel 3 will be imparted by the crank 13 and pitman 12 to the pump rod 11 so that the latter will be reciprocated and will pump oil from the reservoir 7 through 90 the pipe 8, the cylinder 9, the pipe 15, the chamber 16, the pipe 17, and its two branches 18, 19. The oil forced into the branch or discharge pipe 18 is fed through the nozzle 21 to the cable 5 in such quantities as may be permitted by the adjustment of the regulating valve while the surplus oil passes back to the reservoir through the over flow pipe 19, 22.

95 From the foregoing it will be seen that when the device is applied to the tramway carriage and regulated, it will be entirely automatic in its operation and will effectively oil the track cable. It will also be noted that it is of simple construction so that it may be produced at a small cost and will not be liable to get out of working order.

100 Having thus described my invention what I claim and desire to secure by Letters Patent is:

110 1. In a device of the character described, a carriage body, a track wheel journaled thereon, a crank on the axle of said wheel, an

- oil reservoir upon the carriage, an upright pump cylinder supported above the carriage and provided with a reciprocating piston, a pitman connecting the rod of said piston to said crank, a suction pipe leading from the oil reservoir to the inlet of the pump, a discharge pipe in communication with the outlet of the pump and provided with upper and lower branches, the upper branch being adapted to serve as an overflow to return oil to the reservoir, a nozzle arranged at the lower end of the lower branch to discharge oil upon the track for said wheel and a controlling valve arranged in said lower branch.
2. In a device of the character described, a carriage having a track wheel, an oil reservoir upon the carriage, a pump to be actuated from said track wheel, and a vertical pipe connected intermediate its ends to the pump and having at its lower end a discharge nozzle, its upper end being extended to provide an overflow pipe leading to the reservoir.
3. In a device of the character described, a carriage consisting of a body, supporting wheels journalized upon the body adjacent to its ends, supporting brackets connected to the opposite sides of the body, an oil reservoir supported between said brackets at one end of the carriage, an upright or support upon the body, a pump arranged upon said support and having a reciprocating plunger, a connection between the inlet of the pump and the reservoir, a crank upon the shaft of one of said wheels, a pitman connecting the crank and the plunger of the pump, a vertical pipe connected intermediate its ends to the discharge of the pump and having at its lower end a discharge nozzle, the upper end of said pipe being extended to provide an overflow or return pipe leading to the reservoir, and a controlling valve in the lower end of said vertical pipe.
4. In a device of the character described, a carriage having a track wheel, an oil reservoir upon the carriage, the vertical pump arranged upon the carriage, a pump operated from the wheel of the carriage and adapted to elevate oil from the reservoir to said chamber, a horizontal outlet pipe arranged adjacent to the top of said chamber, upper and lower branch pipes leading from the outer end of said horizontal outlet pipe, the upper branch forming an overflow pipe to return oil to the reservoir and the lower branch being adapted to discharge oil upon the track for said wheel and a controlling valve arranged in said lower branch.

In testimony whereof I hereunto affix my signature in presence of two witnesses.

JOSEPH B. BARIANI.
